MIXING MACHINE FOR BOTTLED
CARBONATED BEVERAGES

John R. Adecock, Pikeville, Ky., assignor of one-fourth to John B. Du Puy and one-fourth to J. Kelly Hatmaker, both of Pikeville, Ky.

Application January 25, 1941, Serial No. 375,973

3 Claims. (Cl. 259—57)

This invention relates to a machine for mixing bottled carbonated beverages while the bottles are in their cases, the general object of the invention being to provide a cylinder having a roller track therein over which the cases containing the bottles are moved with means for revolving the cylinder so that the beverages in the bottles are agitated and thus thoroughly mixed, with means for holding the case reaching the rear end of the cylinder against movement until another case is put in the front of the cylinder which releases the holding means and permits the first case to move out of the cylinder upon a delivery track.

Another object of the invention is to provide means whereby the cylinder is rotated a half turn each time a pedal is actuated.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevational view of the invention.

Figure 2 is a top plan view thereof.

Figure 3 is a front end view.

Figure 4 is a transverse vertical sectional view.

Figure 5 is a longitudinal vertical sectional view.

In these views the letter A indicates an upright frame, the lower part of which supports a motor M and the upper part of which adjacent one side of the frame rotatably supports a shaft 1 and belt and pulley means shown generally at 2 connects the motor shaft with the shaft 1 so that the shaft is rotated from the motor. This shaft carries a pair of grooved wheels 3. A stationary shaft 4 is supported in the top of the frame adjacent the other side thereof and this shaft has rotatably mounted thereon a pair of grooved idle wheels 5, these wheels being arranged opposite the wheels 3. A cylinder C includes a pair of rings 6 adapted to be engaged and be seated on the wheels 3 and 5 and the cylinder is rotated when the rings are engaging the drive wheels 3 of the shaft 1. However, cams 7 are arranged on a shaft 8 journaled in the frame and when this shaft is in a certain position the cams will engage either one of a pair of longi-

tudinally extending strips 9 of the cylinder so that the rings are held out of contact with the wheels 3 and thus the cylinder will not be rotated. However, as soon as the shaft 8 is moved to a position where the cams 7 are moved out of engagement with a strip 9 the rings of the cylinder will engage the wheels 3 and thus as the wheels are being rotated by the shaft 1 the cylinder will be rotated. One end of the shaft 8 is formed with a crank arm 10 which is connected by a link 11 with a foot pedal 12 pivoted to an end post of the frame as shown at 13 so that by depressing this pedal the shaft 8 is rocked to move the cams out of engagement with a strip 9 and thus the cylinder is rotated but as soon as the foot is removed from the pedal the parts return to holding position so that after the cylinder has made a half turn the second strip 9 will engage the cams and thus the cylinder will have its rings moved out of contact with the rollers or wheels 3 and thus the cylinder will come to rest after making a half revolution. A spring 14 acts to hold the parts with the cams in holding position.

The cylinder also includes a pair of oppositely arranged channel-shaped shields 14 having flaring front ends 15, the shields being connected to a framework 16 which, in turn, connects with the rings 6. Arranged between the shields is a double track 17 which includes a plurality of upper and lower transversely arranged rollers 18 for removably supporting the cases or boxes B for the bottles B' containing the beverages to be mixed. The front end of the track extends the distance of a case or box beyond the shields so that a box or case can be readily placed on the track and then pushed into the space formed by the shields. The rear end of the track projects slightly beyond the shields and a sloping track 19 receives the boxes or cases from said rear end of the track 17 and delivered into a support of any suitable kind, a portion of which is shown at 20. A pair of holding members or triggers 21 is arranged at the rear end of the track 17 and releasing dogs 22 are arranged at the front end of the track 17 and these dogs move the members 21 to releasing position, when engaged by a box or case through means of rods 23.

Thus it will be seen that when the device is to be used the motor is started so as to start rotary movement of the shaft 1 but as the cams are engaging one of the strips 9 the cylinder is idle.

A box or case of bottles is then placed on the

track 17 and moved to a position under the front end of one of the shields 14. Then the pedal 12 is depressed to move the cams to inoperative position to place the rings of the cylinder on the drive wheels 3. This causes the cylinder to start to rotate and immediately the foot is removed from the pedal so that the cams move back to operated position ready to engage the second strip 9 and thus stop the cylinder after it has made one-half revolution. This places the box of bottles in an up-side-down position as shown in Figure 3. Then a second box of bottles is placed on the second set of rollers of the track 17 and pushed under a shield and then the pedal is depressed again so as to cause rotary movement of the cylinder another half revolution. This brings the first box in an upright position and the second box is turned upside-down. Then a third box is pushed into the cylinder which moves the first box farther into the cylinder and when the pedal is depressed the cylinder makes another half revolution which places the first and third boxes in up-side-down position and the second box in an upright position. Then the fourth box is moved into the cylinder. This operation is continued until the first box reaches the end of the cylinder and the parts are so arranged that when the first box introduced into the cylinder reaches the rear end thereof it is in upright position and ready to be discharged by the introduction of another box and this other box moves the member 22 which results in the rod 23 releasing the member 21 so that the first box is pushed out of the machine by the last box being introduced into the cylinder.

As will be seen the device is very simple and can be manufactured to sell at low cost as it has no complicated internal parts to cause trouble and delay in getting out of order.

It is thought from the foregoing description that the advantages and novel features of the invention will be readily apparent.

It is to be understood that changes may be made in the construction and in the combination and arrangement of the several parts, provided that such changes fall within the scope of the appended claims.

Having described the invention, what is claimed as new is:

1. A mixing device for bottled beverages comprising a frame, a cylinder rotatably supported by the frame, a track passing through the cylinder

for supporting boxes containing the bottles of beverages and parts of the cylinder holding the bottles in the cylinder both when in upright position and in up-side-down position, drive means for rotating the cylinder, manually operated means for normally holding the cylinder out of engagement with the drive means and a pair of members on the cylinder and arranged diametrically on the cylinder for engaging the manually operated means for stopping the cylinder each time it has made a half revolution.

2. In a device of the class described, a frame, idle wheels rotatably arranged in the frame, a shaft rotatably arranged in the frame, drive wheels carried by the shaft, means for rotating the shaft, a cylinder including rings engaging the idle wheels and the drive wheels, manually operated means for normally holding the cylinder with its rings out of contact with the drive wheels, said rings moving into engagement with the drive wheels when the manually operated means are actuated, to cause rotary movement of the cylinder, oppositely arranged shields forming part of the cylinder and extending longitudinally thereof, a double track member passing through the cylinder and between the shields for supporting the objects to be treated and longitudinally extending members in the cylinder for engagement by the means for moving the rings of the cylinder out of engagement with the drive wheels each time a member reaches such means.

3. A device for mixing bottled beverages comprising a frame, a shaft rotatably supported in the frame, a motor for rotating the shaft, drive wheels connected with the shaft, idle wheels supported by the frame opposite the drive wheels, a cylinder, rings connected with the cylinder and engaging the idle wheels and the drive wheels, a third shaft journaled in the frame, cams carried by the third shaft, longitudinally extending strips carried by the cylinder and when engaging the cams said strips act to move the rings away from the drive wheels, manually operated means for rocking the cam shaft to place the cams in operative or inoperative position, a track member passing through the cylinder, upper and lower set of rollers for supporting the boxes containing the bottles, trigger means at the rear end of the track for holding a box against discharging movement, and means at the front end of the track operated by a box placed at the front end of the track for releasing the holding means.

JOHN R. ADCOCK.
